DESIGN FOR A CONDIMENTS SHAKER OR SIMILAR ARTICLE

Boris Blecher, Philadelphia, Pa.

Application November 25, 1944, Serial No. 116,549

Term of patent 14 years

(Cl. D44—22)

To all whom it may concern:

Be it known that I, Boris Blecher, a citizen of the United States, and a resident of Philadelphia, county of Philadelphia, State of Pennsylvania, have invented a new, original and ornamental Design for a Condiment Shaker or Similar Article, of which the following is a specification, reference being had to the accompanying drawings forming a part thereof, wherein:

diments shaker or similar article, showing my new design;

Figure 2 is a rear elevational view thereof; Figure 3 is a side elevational view thereof; and Figure 4 is a top plan view thereof.

I claim:

The ornamental design for a condiment shaker or similar article, as shown.

BORIS BLECHER.
